UNITED STATES PATENT OFFICE.

ISIDOR STARK, OF NEW YORK, N. Y.

SUPPORTING ATTACHMENT FOR PANTS, OVERALLS, AND DRAWERS.

SPECIFICATION forming part of Letters Patent No. 321,654, dated July 7, 1885.

Application filed March 3, 1885. (No model.)

To all whom it may concern:

Be it known that I, ISIDOR STARK, of the city, county, and State of New York, have invented a new and useful Improvement in Supporting Attachments for Pants, Overalls, and Drawers, of which the following is a full, clear, and exact description.

Reference is to be had to the accompanying drawings, forming a part of this specification, in which similar letters of reference indicate corresponding parts in both the figures.

Figure 1 is a front elevation of a pair of boy's pants to which my improvement has been applied, part being broken away. Fig. 2 is a sectional elevation of a part of the same, taken through the broken line *x x*, Fig. 1.

The object of this invention is to promote convenience in the use of pants, overalls, and drawers, and has especial reference to such pants, overalls, or drawers as are provided with the attachments for which Letters Patent No. 312,033 were issued to me February 10, 1885.

The invention consists in the combination, with the body and waistband of a pair of pants, overalls, or drawers provided with suspending loops and eyes and a band for holding the said loops erect, of a curtain provided with button-holes in line with the said loops and eyes, whereby the said curtain can be used to suspend the said pants, overalls, or drawers, when required, as will be hereinafter fully described and then claimed.

A represents a pair of pants, overalls, or drawers, which is provided with a waistband, B, in the ordinary manner. To the body A and the waistband B, at the line of connection, are secured a number of elastic loops, C, which are provided with wire eyes D, or 40 have button-holes formed in them to receive

the buttons that support the said pants. The loops C are held erect by a band or tape, G, passing through the upper parts of the said loops and secured to the waistband B at points between the said loops C. 45

To the body A of the pants, overalls, or drawers and the waistband B, at their line of connection, is secured the upper edge of the curtain E, which hangs free within the said body of the pants. 50

In the curtain E, in line with the loops C and eyes D, are formed button-holes F, which are worked with their wider ends downward or in a reversed position, as shown in Fig. 1. With this construction, should occasion require—as, for instance, by the breaking of one or more of the eyes D or loops C—the curtain E can be folded upward against the inner side of the waistband B, and the button-holes F can be buttoned upon the supporting-buttons, 60 so as to support the pants, overalls, or drawers securely. 55

When not required for use in supporting the pants, the curtain E hangs within the body of the pants in the ordinary manner. 55

Having thus described my invention, I claim as new, and desire to secure by Letters Patent—

The combination, with the body A and waistband B of a pair of pants, overalls, or drawers provided with loops C, eyes D, and band or tape G, of a curtain, E, provided with button-holes F, in line with the said loops and eyes C D, substantially as herein shown and described, whereby the said curtain can be used to suspend the said pants, overalls, or 75 drawers, when required, as set forth. 70

ISIDOR STARK.
